DES 238

10-9-1849

Wes 938

S. G. Jewell & F. H. Root Buffalo N. Y.

Sellers Patent No 938 dated Oct. 9. 1849.

The schedule referred to in these letters forming and making part of the same.

To all whom it may concern: We, do know, that we, Sherman G. Jewell and F. H. Root, of Buffalo, in the County of Erie, and State of New York, have invented or produced a new and ornamental design for a Cooking Stove of which the following is a full description.

reference being had to the accompanying drawing forming part of this specification, in which figure 1. is a plan of one of our Cooking Stoves; figure 2. is a side elevation of the same; figure 3. a front elevation, and figure 4. an elevation of the back.

The general configuration of the Stove, as shew in the figures does not differ materially from others of the same class. The tops of the Stoves as seen in figure 1. is plain with the exception of a border formed of a series of figures f. each composed of leaves and buds. The inclined surface connecting the upper and lower tiers of pot-holes has also a border g. representing leaves overlying each other.

The hearth C. projecting in front of the fire-chamber is surrounded with an arabesque border consisting of a middle chain of figures h. with an indented edging i.

The side of the Stove represented in figure 2. consists mainly of two large panels, the one D. on the end of the fire-chamber, and - which on one of the sides forms the fire door. The panel is sunk and is ornamented with a raised gothic tracery, each compartment of which contains an ornamental scutcheon i. i. The square panel is bordered with an indented edging j. The spaces above and below the panel are filled with an arabesque figures k. k. The rounding front corners of the Stove are ornamented with a series of connected leaves l. l.

The panel E. at the end of the oven has a round-arched top and forms the oven door; it is covered with a plain triple raised gothic tracery each compartment of which contains an ornamental scutcheon m. m.

The edges of the door and the corresponding edges of the

plate are each ornamented with a moulding $\mathfrak{c}$ and the spaces intervening between the door frame moulding and the sides top and bottom of the plates are filled with arabesque patterns m. p. q. r. s.

The front elevation of the stove represented in figure 3. Shows the ornaments of the rounded corner stones distinctly. In the middle of this front are the hinged doors t. t. each covered with a triple gothic panel containing ornamental scutcheons. The door frame is an arabesque pattern of leaves and flowers interchanged and connected. The spaces between the door frame and the corner ornaments are each filled with a raised figure t. t. and the space above the door frame is covered with a series of raised gothic arches a. a. each pair springing from a small corbel.

The back of the stove (figure 4) is merely a sunk panel with a raised moulding v. above which are the damper handles w. w.

The whole is supported on claw-shaped feet x. x. What we claim as our invention and desire to secure by letters patent is the configuration and arrangement of the ornaments herein described, on the several plates of the stove.
